Primary Examiner — Michelle E. Wilson*Assistant Examiner* — Charles Hwang(57) **CLAIM**

The ornamental design for a base station as shown and described.

DESCRIPTION

FIG. 1 is a front, right, perspective view of a base station showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown on the drawings depict portions of the base station that form no part of the claimed design.

1 Claim, 5 Drawing Sheets(56)
